ENGINEERING COMPANY, A CORPORATION OF NEW YORK.

LIQUID-PUMP.

1,028,949.

Specification of Letters Patent. Patented June 11, 1912.

Application filed November 10, 1904. Serial No. 232,097.

To all whom it may concern:

Be it known that I, LEWIS HALLOCK NASH, citizen of the United States, and resident of South Norwalk, in the county of Fairfield and State of Connecticut, have invented a new and useful Improvement in Liquid-Pumps, of which the following is a specification.

My invention relates to improvements in liquid pumps and consists in certain novel improvements in construction and operation, all of which will be pointed out in the claims concluding this specification.

I will now describe the drawings which illustrate my invention in its preferred form, it being understood that I do not confine my invention to the exact form of structure shown, since various modifications may be made without departing from the spirit and scope of my invention, the particular features of novelty which constitute my improvement will be particularly pointed out in the claims concluding these specifications.

Referring to the drawings:—Figure 1. is a longitudinal section through a case-chamber and wheel having my improvements. Fig. 2. is a cross-section of the same.

The case 4. is of a form circular in section having an outlet passage 6. which joins the case-chamber tangentially, and said passage is also preferably made of an enlarging section for a purpose now well understood. The inlet passage 7. enters the central portion of the case-chamber through a port 35 opening 8. which port is located on the side of the shaft opposite to the outlet passage 6.

9. is the propeller wheel, which is mounted on a shaft 10. and said shaft revolves in bearings eccentric to the case-chamber, so that the wheel makes a joint with one side of the case but leaves a passage on the opposite side. This wheel has projecting arms 11. which are preferably curved at the outer ends in the direction of the rotation of the wheel. These arms fill the spaces between the ends of the case chamber, so as to form a joint therewith.

I have shown the impeller wheel as having its blades bent forward in the direction of the rotation of the wheel in such a way that the water which would seek to flow backward against the motion of the wheel will be caught upon the curved ends of these blades and driven up with great force

against the center of the wheel. The effect 55 of this is to retard the flow of the water and to increase the driving force of the wheel, and this takes place in view of the fact that there is no escape for the water through the port at the center of the wheel because the 60 blades make a joint-forming contact with the case walls and effectually separate the water from the inlet port. The whole force, therefore, of this reaction is exerted in an opposite direction to force the water forward in the direction of the wheel, and this action increases the pressure over that which would be due to velocity alone to a very material extent.

Suppose, now that the wheel be caused to 70 revolve in the direction of the arrow; as the wheel blades move forward the spaces included between the case walls and a pair of arms of the wheel will enlarge on the side 14 of the wheel, while upon the side 12, 75 the spaces will be contracting. It is true that the blades do not actually touch the case walls but the spaces may be considered as completed by a prolongation of the blades, and in operation the inertia of the water 80 that fills the chamber will serve to secure the joint between the ends of the blades and the case walls so as to produce a displacing effect. This action being understood, it follows that, as the wheel revolves, the spaces 85 on the side 14 of the wheel will be enlarging and that the water will flow into these spaces through the port 8 until a wheel space arrives at the position 13, when the blade passes over the edge of said port closing 90 communication therewith. As the wheel continues to revolve the water will be compressed in the side 12, of the wheel chamber and forced out of the passage 6. In addition to the pressure produced by this displacing action just described the effect of 95 centrifugal force is also present, the same as in the usual forms of centrifugal pumps, and these two effects reinforce each other, and I have found by actual test that the pressure 100 produced by the revolution of my improved pump at a given speed is more than double that which would be produced in an ordinary form of centrifugal pump.

A difference between my invention and 105 the ordinary form of centrifugal pump will be seen in that the inlet passage of the water does not extend around the center of the case

chamber but the opening is restricted to that portion of the chamber that is enlarging and is separate from the portion of the case chamber that is contracting. Therefore the pressure produced in the contracting portion of the case can not find escape except by, either forcing itself backward against the motion of the wheel, or through the outlet pipe. It will thus be seen that my improved pump is a combined displacement and centrifugal pump.

Having described a structure having my improvements I now claim as my invention:—

- 15 1. In a centrifugal pump, the combination of a casing having an outlet at its circumference, and having an inlet at its center at the side of the center line opposite the outlet passage, combined with an impeller wheel having blades forming contact with the side walls of the casing to separate the inlet and outlet ports.
- 20 2. In a centrifugal pump, a casing, a revolving member forming a fluid tight joint with the casing, at a certain point, an inlet port adjacent the center of the wheel for admitting fluid to one side of said point, and an outlet for the escape of the fluid at the opposite side of said point, said joint separating inlet and outlet columns.
- 25 3. The combination of a casing, a wheel forming a fluid-tight joint with the casing, a fluid inlet adjacent the center of the wheel, on one side of the point where the joint is formed, an outlet in the opposite side of said joint outside the path of rotation of the wheel, said joint separating the inlet and outlet to prevent the back pressure at the outlet from having free escape into the inlet.
- 30 4. The combination of a casing, a wheel having blades forming a fluid-tight joint with the casing, a fluid inlet adjacent the center of the wheel on one side of the point where the joint is formed, an outlet on the opposite side of said joint, said joint separating the inlet and outlet to prevent back pressure at the outlet from having escape to

the inlet, said blades being directed forward in the direction of rotation of the wheel.

5. In a centrifugal pump, a casing, a revolving impeller member forming a fluid-tight joint with said casing at a certain point, said revolving impeller member having reaction blades extending forward in the direction of the rotation of the pump, an inlet port at the center of the wheel for admitting fluid to one side of said point, an outlet port outside the periphery of the wheel for the escape of the fluid from the opposite side of said point, said joint separating the inlet and outlet columns.

6. The combination of a casing, a wheel forming a fluid-tight joint with the casing, said wheel having arms extending in the direction of the motion of the wheel forming reaction surfaces for impelling the fluid, a fluid inlet at the center of the wheel on one side of the point where the joint is formed between the wheel and the casing, an outlet port on the opposite side of said joint separating the inlet and outlet and outside the periphery of the wheel, the said joint preventing the back pressure at the outlet from having free escape to the inlet.

7. The combination of a casing, a wheel having blades forming a fluid joint with the casing, a fluid inlet within the periphery of the wheel on one side of the point where the joint is formed, an outlet on the opposite side of the said joint, said joint separating the inlet and outlet to prevent back pressure from having escape to the inlet, said blades being directed forward in the direction of rotation of the wheel to provide reaction surfaces for impelling the fluid in the direction of the motion of the wheel.

In testimony, that I claim the foregoing as my invention, I have signed my name in presence of two witnesses, this seventh day of November 1904.

Corrections in Letters Patent No. 1,028,949

It is hereby certified that in Letters Patent No. 1,028,949, granted June 11, 1912, upon the application of Lewis Hallock Nash, of South Norwalk, Connecticut, for an improvement in "Liquid-Pumps," errors appear in the printed specification requiring correction as follows: Page 2, line 35, for the word "in" read *on*, and same page, line 76, for the compound word "fluid joint" read *fluid-tight joint*; and that the said Letters Patent should be read with these corrections therein that the same may conform to the record of the case in the Patent Office.

Signed and sealed this 16th day of July, A. D., 1912.

Acting Commissioner of Patents.

chamber but the opening is restricted to that portion of the chamber that is enlarging and is separate from the portion of the case chamber that is contracting. Therefore the pressure produced in the contracting portion of the case can not find escape except by, either forcing itself backward against the motion of the wheel, or through the outlet pipe. It will thus be seen that my improved pump is a combined displacement and centrifugal pump.

Having described a structure having my improvements I now claim as my invention:—

- 15 1. In a centrifugal pump, the combination of a casing having an outlet at its circumference, and having an inlet at its center at the side of the center line opposite the outlet passage, combined with an impeller wheel having blades forming contact with the side walls of the casing to separate the inlet and outlet ports.
- 20 2. In a centrifugal pump, a casing, a revolving member forming a fluid tight joint with the casing, at a certain point, an inlet port adjacent the center of the wheel for admitting fluid to one side of said point, and an outlet for the escape of the fluid at the opposite side of said point, said joint separating inlet and outlet columns.
- 25 3. The combination of a casing, a wheel forming a fluid-tight joint with the casing, a fluid inlet adjacent the center of the wheel, on one side of the point where the joint is formed, an outlet in the opposite side of said joint outside the path of rotation of the wheel, said joint separating the inlet and outlet to prevent the back pressure at the outlet from having free escape into the inlet.
- 30 4. The combination of a casing, a wheel having blades forming a fluid-tight joint with the casing, a fluid inlet adjacent the center of the wheel on one side of the point where the joint is formed, an outlet on the opposite side of said joint, said joint separating the inlet and outlet to prevent back pressure at the outlet from having escape to

the inlet, said blades being directed forward in the direction of rotation of the wheel.

5. In a centrifugal pump, a casing, a revolving impeller member forming a fluid-tight joint with said casing at a certain point, said revolving impeller member having reaction blades extending forward in the direction of the rotation of the pump, an inlet port at the center of the wheel for admitting fluid to one side of said point, an outlet port outside the periphery of the wheel for the escape of the fluid from the opposite side of said point, said joint separating the inlet and outlet columns.

6. The combination of a casing, a wheel forming a fluid-tight joint with the casing, said wheel having arms extending in the direction of the motion of the wheel forming reaction surfaces for impelling the fluid, a fluid inlet at the center of the wheel on one side of the point where the joint is formed between the wheel and the casing, an outlet port on the opposite side of said joint separating the inlet and outlet and outside the periphery of the wheel, the said joint preventing the back pressure at the outlet from having free escape to the inlet.

7. The combination of a casing, a wheel having blades forming a fluid joint with the casing, a fluid inlet within the periphery of the wheel on one side of the point where the joint is formed, an outlet on the opposite side of the said joint, said joint separating the inlet and outlet to prevent back pressure from having escape to the inlet, said blades being directed forward in the direction of rotation of the wheel to provide reaction surfaces for impelling the fluid in the direction of the motion of the wheel.

In testimony, that I claim the foregoing as my invention, I have signed my name in presence of two witnesses, this seventh day of November 1904.
